COMBINED LAMP AND TELEPHONE STAND

Henry A. Glaeser, Wilmington, Del.

Application September 20, 1948, Serial No. 148,670

Term of patent 7 years

(Cl. D48—20)

To all whom it may concern:

Be it known that I, Henry A. Glaeser, a citizen of the United States, residing at Wilmington, in the county of New Castle and State of Delaware, have invented a new, original, and ornamental Design for Combined Lamp and Telephone Stand, of which the following is a specification, reference being had to the accompanying drawing, forming part hereof.

Figure 1 is a front perspective view of a combined lamp and telephone stand showing my new design and Figure 2 is a rear elevational view thereof, the shade and part of the stand being omitted for convenience of illustration.

I claim:

The ornamental design for a combined lamp and telephone stand, as shown.

HENRY A. GLAESER.
